UNITED STATES PATENT OFFICE

EDWIN B. SCHOONMAKER, OF SAUGERTIES, NEW YORK, ASSIGNOR TO THE TISSUE COMPANY, OF SAUGERTIES, NEW YORK, A CORPORATION OF NEW YORK

DESIGN FOR A PAPER NAPKIN OR THE LIKE

Application filed July 23, 1929. Serial No. 32,171. Term of patent 7 years.

To all whom it may concern:

Be it known that I, EDWIN B. SCHOONMAKER, a citizen of the United States, and a resident of Saugerties, in the county of Ulster and State of New York, have invented the new, original and ornamental Design for Paper Napkins or the like, of which the following is a specification.

Reference is to be had to the accompanying drawing, in which

Fig. 2 is an edge view of Fig. 1.

I claim:

The ornamental design for a paper napkin or the like, as shown.

EDWIN B. SCHOONMAKER.
